UNITED STATES PATENT OFFICE.

LUCY COTTON AMENT, OF NEW YORK, N. Y.

DESIGN FOR A HANDLE FOR ARTICLES.

Application filed August 3, 1927. Serial No. 22,985. Term of patent 14 years.

To all whom it may concern:

Be it known that I, LUCY COTTON AMENT, a citizen of the United States, residing at New York city, in the county of New York and State of New York, have invented a new, original, and ornamental Design for Handles for Articles, of which the following is a specification, reference being had to the accompanying drawing, forming part thereof.

Fig. 1 is a side elevation of a handle for articles showing my new design; Fig. 2 is a side elevation taken at 90° from that shown in Fig. 1.

I claim:

The ornamental design for a handle for articles as shown.
